ABSTRACT: This disclosure relates to a shirring attachment for sewing machines equipped with differential feeding mechanisms, and includes a bracket pivotally carrying an arm which in turn carries a shirring blade, the arm and bracket having cooperative abutment means for locating the arm in operative and inoperative positions thereof, and biasing means for positively though releasably maintaining the abutment means in contacting engagement in both positions of the arm. The shirring blade is pivotally journaled to the arm for rotation of about a horizontal axis, and cam and cam follower means are provided for automatically pivoting the shirring blade to an inoperative position upon the pivoting movement of the arm to its inoperative position.

SHIRRING ATTACHMENT FOR SEWING MACHINES

Sewing machines having a differential feed mechanism are particularly useful to produce a shirring or similar effect by advancing one workpiece or member, entering into a finished product, at a faster rate than the normal feed of the work as a whole in the region of stitch formation. In performing certain types of work it is at times desirable to shirr a portion of the work during a part of a seam forming operation, but not during other parts of such operation. During certain seaming operations it may be undesirable to shirr or ruffle the material, and the shirring mechanism must therefore also be capable of movement to an inoperative position to clear the throat plate area.

A shirring attachment which is capable of functioning in the manner heretofore described is disclosed in U.S. Pat. No. 2,965,056 granted on Dec. 20, 1960, to Wallenberg et al. The shirring attachment disclosed in this patent includes a mounting bracket carrying an arm journaled for pivoting movement about a vertical axis to swing the shirring blade 180° between operative and inoperative positions. In addition, the shirring blade is pivotally journaled about a horizontal axis in order that in the operative position the shirring blade can be pivoted downwardly toward the feed dogs if shirring operation is desired or upwardly to temporarily terminate the shirring operation without swinging the entire arm to its inoperative position. Though this conventional shirring attachment has been found satisfactory for most purposes, several disadvantages thereof have been overcome by the present invention. For example, the shirring blade carrying arm of the present shirring attachment is positively though releasably maintained in both the operative and inoperative positions thereof by means of a spring which continually urges cooperative abutment shoulders of the arm and the mounting bracket into contacting engagement. Due to the cooperative abutting surfaces of the arm and the bracket, the shirring blade is positively maintained in its exact position relative to the feed dogs yet can be readily and rapidly moved to an inoperative position where it is again positively maintained until returned by the operator.

The shirring device further includes a finger carried by the shaft of the shirring blade which overlies the presser foot whereby upon upward movement of the presser foot the shirring blade is automatically pivoted away from the feed dogs and the throat plate to provide ready access to this area by the operator. Upon the downward movement of the presser foot a return spring automatically biases the shirring blade to its operative position in engagement with the feed dogs.

Another advantage of the shirring attachment is the provision of cooperative cam and cam follower means between the mounting bracket and arm such that upon the swinging movement of the arm to its inoperative position the shirring blade is automatically progressively lifted away from the differential feed dogs and/or the work toward its inoperative position.

In addition to the foregoing advantages, the shirring attachment is relatively compact thereby facilitating the mounting of the attachment on most sewing machines having differential feed mechanisms.

In keeping with the foregoing, it is therefore a primary object of this invention to provide a novel shirring attachment possessing the advantages heretofore noted, the attachment including a mounting bracket, an arm carried by the bracket, means journaling the arm to the bracket for pivoting movement about a generally vertical axis between operative and inoperative positions thereof, a shirring blade carried by the arm, and means for positively though releasably maintaining the arm in each of the operative and inoperative positions thereof by applying relative biasing force between the arm and the bracket to maintain cooperative abutment surfaces thereof in contacting engagement in both the operative and inoperative positions of the arm.

A further object of this invention is to provide a shirring attachment of the type heretofore defined wherein the cooperative abutment means are formed by a locating abutment sur-

face of the bracket and a pair of abutment surfaces of the arm defining therebetween an angle generally equal to the angle setoff between the operative and inoperative positions of the arm.

Still another object of this invention is to provide a novel shirring attachment of the type heretofore set forth wherein the journaling means includes a pivot pin journaled in an elongated slot of the bracket, the arm being carried by the pivot pin, and the biasing force being applied by a spring continually urging the pivot pin and the arm carried thereby toward one end of the elongated slot and a locating abutment surface of the bracket to maintain the cooperative abutment means in contacting though disengageable relationship in both the operative and inoperative positions of the arm.

Another object of this invention is to provide a novel shirring attachment which includes a shirring blade carried by a shaft having a horizontal axis and means responsive to the pivoting of the arm about the first-mentioned journaling means for automatically pivoting the shaft and the shirring blade carried thereby upon pivoting movement of the arm to this inoperative position.

A further object of this invention is to provide a novel shirring attachment of the type immediately heretofore described wherein the automatic movement of the shirring blade is effected by a cam follower adjustably secured to the shaft for varying the throw thereof and a cam surface of the bracket.

With the above and other objects in view that will hereinafter appear, the nature of the invention will be more clearly understood by reference to the following detailed description, the appended claimed subject matter, and the several views illustrated in the accompanying drawings.

IN THE DRAWINGS:

FIG. 1 is a fragmentary top plan view of a sewing machine equipped with an intermittent differential feed mechanism, and illustrates the shirring attachment of this invention secured thereto with an arm carrying a shirring blade disposed in its operative position.

FIG. 2 is a fragmentary front elevational view of the sewing machine of FIG. 1, and illustrates a torsion spring normally urging the shirring blade to its operative position.

FIG. 3 is an end elevational view of the sewing machine, and illustrates a finger connected to the shirring blade shaft in overlying relationship to a presser foot of the sewing machine whereby upward movement of the latter automatically pivots the shirring blade to an inoperative position.

FIG. 4 is an enlarged top plan view of the shirring attachment illustrating the shirring blade in its operative position in overlying relationship to the differential feed dogs, and biasing means for positively though releasably holding the arm in its operative position.

FIG. 5 is a top plan view of the shirring attachment of FIG. 4, and illustrates the arm in an inoperative position 90° removed from that shown in FIG. 4.

FIG. 6 is an enlarged side elevational view of the shirring attachment as viewed in FIG. 2 but detached from the sewing machine, and illustrates a cam follower adjustably carried by an end of the shaft opposite the shirring blade.

FIG. 7 is an end elevational view of the shirring attachment looking from left-to-right in FIG. 6, and more clearly illustrates the cam follower carried by the shirring blade shaft and a cam surface of the mounting bracket.

FIG. 8 is a fragmentary sectional view taken generally along line 8-8 of FIG. 6, and illustrates the manner in which a spring normally urges the arm to its operative position through a pivot pin thereof.

FIG. 9 is a bottom view of the shirring attachment partially in cross section, and illustrates the manner in which a spring normally biases the shirring blade to its operative position.

FIG. 10 is a cross-sectional view taken generally along line 10-10 of FIG. 6, and more clearly illustrates the manner in which the cam follower is adjustably secured to the shirring blade shaft.

Referring particularly to FIGS. 1 through 3 of the drawings, a sewing machine 10 of the type more fully disclosed in the noted Wallenberg et al. patent is provided with a shirring attachment 15 mounted in a manner to be described more fully hereinafter. Reference may be had to the Wallenberg et al. patent for details of the machine 10 which are unnecessary for a complete understanding of the shirring attachment 15. However, it will be noted that the machine 10 includes a presser foot 11 (FIG. 3) cooperating with a main feed dog 12 and a differential feed dog 13 (FIG. 4) whose teeth are exposed through openings (unnumbered) in a plate 14 which is suitably secured to a portion of the sewing machine housing (unnumbered). The shirring attachment is secured to the sewing machine 10 in such a manner that in the operative position a shirring blade 16 thereof is positioned in front of the presser foot 11, as best shown in FIG. 3, and is yieldingly urged downwardly against the differential feed dog 13 and thereby serves to shirr or ruffle the material as it is fed thereunder to the needle in a manner more fully described and illustrated in the latter-noted patent.

Reference is now made more particularly to FIGS. 4 through 10 of the drawings, wherein the shirring attachment 15 will be seen to include a mounting bracket, generally designated by the reference numeral 17, having a vertical platelike portion 18 provided with elongated openings 20, 21 (FIGS. 7 and 8). The surface (unnumbered) of the bracket portion 18 shown in FIG. 8 is seated against the housing (unnumbered) of the sewing machine 10 as shown in FIG. 1, and fastened thereto by screws 22 passing through the openings 20, 21 and secured in threaded bores (unnumbered) of the machine housing. The slots 20, 21 permit the shirring attachment 15 to be adjusted vertically for proper positioning of the shirring blade 16 relative to the feed dog 13.

A horizontal portion 23 of the bracket 17 is provided with an elongated slot 24 (FIGS. 4, 5 and 8) having opposite arcuate end faces 25, 26 (FIG. 8). A stub shaft or pivot pin 27 is positioned in the slot 24, as best shown in FIG. 8, with an enlarged head 28 thereof resting atop an upper surface 30 of the horizontal portion 23. A threaded end portion (unnumbered) of the pin 27 passes through an opening 31 of an arm 32 which is secured to the pivot pin 27 by a nut 33. The axis of the pin 27 is generally vertical and the arm 32 is therefore free to pivot or swing about the axis of the pin 27 in a horizontal plane between the operative position shown in FIG. 4 and the inoperative position of FIG. 5. In addition, because of the elongated nature of the slot 24, the arm 32 may be shifted to the left as viewed in FIG. 8 against the biasing force of a spring 34 housed in a bore 35 of the horizontal portion 23 and bearing against the pivot pin 27. The tension of the spring 34 can be adjusted by means of a set screw 36 received in a threaded counterbore 37 which also includes a locking screw 38. The purpose of the spring 34 is to maintain cooperative abutment means 40, 41 (FIG. 9) of the bracket 17 and the arm 32 in contacting engagement in the operative position of the arm 32 and abutment means 40, 42 in contact in the inoperative position of the arm 32 (FIG. 5). As best shown in FIG. 9, the abutment means 41, 42 of the arm 32 are merely end faces of the arm which are disposed at an angle of 90° relative to each other and which merge with each other by a radius 43. The abutment means 40 of the bracket 17 is merely a shoulder which will flushingly engage the end faces 41, 42 in the respective operative and inoperative positions illustrated in FIGS. 4 and 5.

Referring particularly to FIG. 4, when it is desired to move the arm 32 from the operative position illustrated therein, the same is swung in the direction of the unnumbered headed arrow which progressively pivots the arm 32 about the axis of the pivot pin 27. During this movement the radius 43 bears against the surface 40 and progressively shifts the pivot pin 27 away from the end face 25 of the slot 24 during which time the spring 34 is progressively collapsed. After the arm 32 has been swung approximately 45° from that illustrated in FIG. 4, the shoulder 43 passes to the left of the axis of the pivot pin 27, as viewed in FIG. 4, and the force of the spring 34 returns the pin

27 toward the end face 25 with a snaplike motion bringing the surface 42 of arm 32 into contact with the shoulder 40, as shown in FIG. 5. When it is desired to return the arm 32 from the inoperative position shown in FIG. 5 to the operative position of FIG. 4, the arm 32 is swung clockwise as viewed in FIG. 5 whereupon the shoulder 43 again bears against the surface 40 shifting the pivot pin 27 downwardly, as viewed in FIG. 5, until such a time as the arm 32 has been pivoted approximately 45° after which the compressed spring 34 will return the arm 32 with a snapping action to the operative position of FIG. 4. From the foregoing it will be noted that the cooperative abutment means 40-42 in cooperation with the spring biased shiftable mounting of the pivot pin 27 functions to maintain the arm 32 positively though releasably positioned in both the operative and inoperative conditions of the arm 32.

The arm 32 includes a threaded bore 45 (FIGS. 4 and 5) in which is threadably received an adjusting screw 46 having an exposed end 47 and a locking screw 48. In the operative position (FIG. 4) of the arm 32 the exposed end 47 of the adjusting screw 46 contacts a face 50 of the mounting bracket 17. As is best visualized in FIG. 4, the screw 46 can be adjusted inwardly or outwardly of the threaded bore 45 to accurately adjust the position of the shirring blade 16 in its operative position by limiting the pivoting movement of the arm 32 to a point at which the face of the screw 46 contacts the surface 50.

The underside of the arm 32 includes a housing 51 in which is rotatably journaled a shaft 52 having oppositely exposed ends 53, 54. The end 53 of the shaft 52 has the shirring blade 16 attached thereto by means of a slot 55 and fasteners 56 (FIGS. 5 and 7). A midportion of the shaft 52 is received in a bore 57 (FIG. 9) of the housing 51 and carries a pair of collars 60, 61 having respective reduced end portions 62, 63 received in the bore 57. A torsion spring 65 surrounds the shaft 52 and the ends (unnumbered) thereof are received in openings 66, 67 of the respective collars 60, 61. The collar 61 preferably has a plurality of notches 68 (FIG. 10) for receiving a wrenchlike tool for rotating the collar 61 to increase or decrease the tension of the spring 65. A set screw 70 secures the collar 61 in any desired adjusted position thereof, and in a like manner the collar 60 can be secured in any desired position of rotation relative to the shaft 52 by means of a set screw 71. The spring 65 serves to urge the shaft 52 in a counterclockwise direction as viewed in FIGS. 3 and 7 to hold the rearward free end of the shirring blade 16 in cooperative relationship to the feed dog 13.

The collar 60 additionally includes a lifting finger 72 having an end portion 73 partially overlying the shirring blade 16 and in the operative position of the arm 32 (FIGS. 1, 3 and 4) the end 73 of the lifting finger 72 overlies the presser foot 11, as is best illustrated in FIG. 3. Therefore, upon the upward movement of the presser foot 11 in a conventional manner, the lifting finger 72 is rotated clockwise, as viewed in FIG. 3, to thereby automatically rotate the shaft 52 through the collar 60 and raise the shirring blade 16 away from the feed dog 13. Since the collar 60 can be set in any particular position of rotation relative to the shaft 52 by the set screw 71, the degree which the shirring blade 16 is lifted can be adjusted by positioning the end 73 of the lifting finger 72 at any desired position above the presser foot 11. It should, however, be noted that upon changing the position of the collar 60 an increase or a decrease in the tension of the spring 65 will take place, and this may have to be compensated for by the rotation of the collar 61 in the manner heretofore described. However, this construction also permits the tension of the spring 65 to be varied by adjusting the collar 60 relative to the shaft 52.

The shirring attachment is also provided with means responsive to the movement of the arm 32 from the operative position (FIG. 4) to the inoperative position (FIG. 5) to automatically progressively rotate the shaft 52 and thus lift the shirring plate 16. This function is provided by a cam follower 75 (FIGS. 7 and 9) forming an extension of a collar 76 which is adjustably secured in any desired position to the exposed end

54 of the shaft 52. The cam follower 75 is in alignment with a cam surface 78 formed in the undersurface (unnumbered) of the horizontal portion 23. Referring particularly to FIGS. 7 and 9 in which the arm 32 is illustrated in the operative position with the stirring blade 16 adjacent the feed dog 13, clockwise pivoting of the arm 32, as viewed in FIG. 9, progressively causes the cam follower 75 to be guided along the cam surface 78 resulting in a clockwise rotation of the shaft 52, as viewed in FIG. 7, and thus an upward lifting of the rearward end of the stirring blade 16. Likewise, upon pivoting movement of the arm 32 from the inoperative position shown in FIG. 5 to the operative position shown in FIG. 4 the spring 65 will progressively return the stirring blade 16 to its operative position (FIG. 7) as the cam follower 75 progressively moves along the cam surface 78. In this manner any movement of the arm 32 is accompanied by an automatic lifting or lowering of the stirring blade 16.

The cam follower 75 may also be provided with an opening 80 (FIGS. 7 and 10) through which may be attached a link of a foot-treadle operated chain for pivoting the stirring blades 16 at times other than those heretofore described.

While preferred forms and arrangements of parts have been shown in illustrating the invention, it is to be clearly understood that various changes in details and arrangement of parts may be made without departing from the spirit and scope of this disclosure.

We claim:

1. A stirring attachment for a differential feed sewing machine comprising a mounting bracket, a pivot pin, means mounting said pivot pin for transverse shifting movement relative to said bracket and to the pivot pin axis, an arm received on said pivot pin for pivotal movement about the axis thereof between operative and inoperative positions, a rotary shaft journaled on said arm, a stirring blade carried by said rotary shaft, spring means engaging said rotary shaft for biasing said shaft in a predetermined angular direction, means limiting said angular distance between said operative and said inoperative positions to 90°, and means for positively through reasonably maintaining said arm in each of said operative and inoperative positions.

2. The stirring attachment as defined in claim 1 wherein said maintaining means includes cooperative abutment means of said arm and mounting bracket which are in contacting engagement in the operative and inoperative positions of said arm.

3. The stirring attachment as defined in claim 1 wherein said maintaining means includes means for biasingly maintaining said arm in each of the operative and inoperative positions thereof.

4. The stirring attachment as defined in claim 1 wherein said maintaining means includes cooperative abutment means and means for biasingly maintaining said abutment means in contacting engagement in the operative and inoperative positions of said arm.

5. The stirring attachment as defined in claim 2 wherein said cooperative abutment means are defined by a locating abutment surface of said bracket, and a pair of abutment surfaces of said arm defining therebetween an angle generally equal to the angle set-off between the operative and inoperative positions of said arm.

6. The stirring attachment as defined in claim 3 wherein said biasing means is a spring, and means are provided for adjusting the tension of said spring for selectively varying the holding force of said maintaining means.

7. The stirring attachment as defined in claim 3 wherein said pivot pin is journaled in an elongated slot of said bracket, and said biasing means applies a force continually urging said pivot pin toward one end of said elongated slot.

8. The stirring attachment as defined in claim 3 wherein said maintaining means further includes cooperative abutment means of said arm and mounting bracket which are in contacting engagement in the operative and inoperative positions of said arm, and said biasing means biasingly maintains said

cooperative abutment means in contacting engagement in the operative and inoperative positions of said arm.

9. The stirring attachment as defined in claim 8 wherein said pivot pin is journaled in an elongated slot of said bracket, and said biasing means applies a force continually urging said pivot pin toward an end of said elongated slot and toward the abutment means of said bracket.

10. The stirring attachment as defined in claim 9 wherein said cooperative abutment means are defined by a locating abutment surface of said bracket and a pair of abutment surfaces said arm said arm defining therebetween an angle generally equal to the angle setoff between the operative and inoperative positions of said arm, and said elongated slot has a longitudinal axis disposed generally normal to said locating abutment surface.

11. The stirring attachment as defined in claim 10 wherein said biasing means is a spring, and means are provided for adjusting the tension of said spring for selectively varying the force applied to said cooperative abutment means in both the operative and inoperative positions of said arm.

12. A stirring attachment for a differential sewing machine comprising a mounting bracket, an arm carried by said bracket, first means journaling said arm to said bracket for pivoting movement about a generally vertical axis between operative and inoperative positions thereof, stirring blade means carried by said arm, second means journaling said stirring blade means to said arm for pivoting movement about a generally horizontal axis, and means responsive to the pivoting of said arm relative to said bracket about said first journaling means for automatically pivoting said stirring blade means about said second journaling means.

13. The stirring attachment as defined in claim 12 wherein said responsive means is defined by cooperative cam and cam follower means.

14. The stirring attachment as defined in claim 12 wherein said responsive means is defined by cooperative cam and cam follower means, one of said cam and cam follower means being carried by said bracket, and the other of said cam and cam follower means being carried by said stirring blade means.

15. The stirring attachment as defined in claim 12 including means carried by said stirring blade means for overlying a presser foot of a sewing machine to impart pivoting movement to said stirring blade means about said second journaling means upon upward movement of the presser foot.

16. The stirring attachment as defined in claim 13 wherein said second journaling means includes a shaft carrying said cam follower means, and said cam means is defined by a cam surface in alignment for contact by said cam follower means during the pivoting of said arm about said first journal means.

17. The stirring attachment as defined in claim 16 including means to selectively vary the throw of said cam follower means to vary the amount of pivoting movement of said stirring blade means.

18. The stirring attachment as defined in claim 17 wherein said second journaling means includes a shaft carrying said cam follower means, and said varying means is operative to fixedly secure said cam follower means at any one of a plurality of different positions about the circumference of said shaft.

19. The stirring attachment as defined in claim 12 including means for positively though releasably maintaining said arm in each of the operative and inoperative positions thereof, said maintaining means being defined in part by said first journaling means, said first journaling means including a shaft journaled in an elongated slot of said bracket, and biasing means for applying a force continually urging said shaft toward an end of said elongated slot.

20. The stirring attachment as defined in claim 19 wherein said maintaining means further includes cooperative abutment means of said arm and bracket, and said cooperative abutment means are maintained in contacting engagement in the operative and inoperative positions of said arms by said biasing means.

21. The stirring attachment as defined in claim 1 wherein the pivotal movement of said arm relative to said pivot pin is about a generally vertical axis and the rotary motion of said stirring blade is about a generally horizontal axis, and means

responsive to the pivoting of said arm relative to said pivot pin for automatically rotating said rotary shaft and the stirring blade carried thereby about said horizontal axis.
